UNITED STATES PATENT OFFICE

CLARENCE H. SCRUGGS, OF BROOKLYN, NEW YORK

JEWELRY DISPLAY DEVICE

Application filed June 7, 1932. Serial No. 615,939.

This invention relates to a display device for jewelry, and precious stones.

The primary object of the invention resides in a display device by which jeweled rings and the like may be illuminated to show off the true qualities of the same.

Another feature of the invention is to provide a display device which may be placed in a store window for attractively displaying articles of jewelry and to attract attention of passers-by by reason of the brilliancy thereof.

A further object is to support jeweled rings and like articles of jewelry within the path of artificial light rays so that the jeweled settings will produce a colorful and brilliant display.

A still further object of the invention is the provision of a display tray for articles of jewelry having the above features which facilitate the easy and convenient changing of the article displayed.

With these and other objects in view, the invention resides in the certain novel construction, combination and arrangement of parts, the essential features of which are hereinafter fully described, are particularly pointed out in the appended claims, and are illustrated in the accompanying drawings, in which:

Figure 1 is a top plan view of my illuminated jewelry display device.

Figure 2 is a vertical longitudinal sectional view on the line 2—2 of Figure 1.

Figure 3 is a vertical transverse sectional view on the line 3—3 of Figure 1.

Figure 4 is a perspective view showing the manner in which an article holder may be separated from its support.

Figure 5 is an enlarged detail longitudinal sectional view of a slight modification.

Figure 6 is a vertical transverse sectional view on the line 6—6 of Figure 5.

Referring to the drawings by reference characters, the numeral 10 designates my improved jewelry display device in its entirety which comprises a tray or body 11 which is provided with a plurality of spaced parallel compartments or recesses 12, which are closed at one end by a partition wall 13, while the opposite ends are opened, but may be closed

by a door 14 hinged to the body 11 as at 15, and which door is common to all of the compartments for closing the same when and for the purpose hereinafter described. When the door 14 is swung to a closed position, the same may be secured by hooks 16 pivoted to opposite sides of the body 11 and which are engageable with eyes 17 carried at opposite ends of the door 14.

The partition wall 13 is disposed in spaced relation with respect to an end wall 18 to provide a compartment 19 disposed at one end of the compartment 12, and at right angles thereof.

Fixedly mounted in the partition wall 13 and respectively disposed within the compartments 12 are reflector tubes 20 which communicate with the compartment 19 but extend short of the open end of the compartments 12.

Mounted within the compartment 19 and in axial alinement with the respective reflector members 20 are electric lamp sockets 21 which threadedly receive elongated electric lamps or bulbs 22. These lamps may be of incandescent or gaseous type, and may be of varied colors. The wires 23 leading from the lamp sockets are embodied in a single cord 24 having an attachment plug 25 at the free end thereof to enable the device to be electrically connected with a source of electric supply.

Slidable over the reflector tubes 20 are holder tubes 26 which are provided with spaced openings 27 which are brought into register with the openings 28 provided in the upper side of the reflector members 20. It is of course understood that the holder tubes 26 are inserted upon the reflector tubes when the door 14 is swung to an open position and when the door is closed, the bosses 29 on the inner side of the door act as supports for one end of the holder tubes, while the opposite end abuts the partition wall 13.

In practice, the jeweled rings to be displayed are inserted upon the holder tubes 26 before the said tubes are inserted over the reflector tubes 20, and in the drawings only one ring has been shown, but it will be noted that the jeweled setting of the ring is disposed above the registering openings 27 and 28. When the tray is filled up with rings suitably

positioned with the settings over the respective openings, and electric lamps 22 are lighted, a brilliant display will be produced. Although I have illustrated the invention for 5 use in connection with jeweler rings, other articles of jewelry may be similarly displayed, such as pearls, uncut stones and the like. If desired, the holder tubes may be of various diameters to accommodate rings of different 10 sizes.

In Figures 5 and 6 of the drawings, I have shown a slightly modified form wherein a layer of asbestos or other heat insulating material 30 is carried by the inner wall of the 15 holder tube 26, while a covering of velvet, silk or the like 31 is carried by the exterior walls of the said holder tube. The heat insulating material 30 tends to prevent the excessive heating up of the holder tube, while the outer 20 covering of material 31 lends to the attractiveness of the device, and provides a soft friction surface over which the rings may be passed.

In addition to enclosing the electric lamps, the reflector tubes 20 have their inner walls 25 highly polished for the purpose of reflecting light from within the tube through the registering openings 27 and 28.

While I have shown and described what I 30 deem to be the most desirable embodiment of my invention, I wish it to be understood that various changes as come within the scope of the appended claims may be resorted to if desired.

35 Having thus described the invention, what I claim as new and desire to secure by Letters Patent is:—

1. A jewelry display device comprising a 40 base, spaced tubes fixedly mounted upon said base, and having openings therein, illuminating means within said tube, tubular holder members slidably telescoping said tubes, and having openings therein in register with the 45 openings in said tube, and over which the jewels to be displayed are positioned.

2. A jewelry display device comprising a 50 base, spaced tubes fixedly mounted upon said base, and having openings therein, illuminating means within said tube, tubular holder members slidably telescoping said tubes, and having openings therein in register with the 55 openings in said tube, and over which the jewels to be displayed are positioned, and means for preventing accidental sliding movement of said tubular members when the same are fully inserted upon said tubes.

3. A jewelry display device comprising a 60 tray having separate compartments therein which are open at one end, reflector tubes disposed within said compartments and mounted in spaced relation to the bottom walls thereof, said tubes having spaced openings therein, holder tubes telescoping said reflector tubes and having spaced openings 65 therein in register with the openings in said

tubes, a hinged door closing the open ends of said compartments, and electric lamps disposed within said reflector tubes.

4. A jewelry display device comprising a 70 tray having separate compartments therein which are open at one end and closed at their opposite ends, reflector tubes fixedly mounted in the closed ends of said compartments and extending thereinto in spaced relation to the walls thereof, said tubes having spaced openings 75 therein, electric lamp sockets mounted in the closed end walls of said compartments, electric lamps carried by said sockets and extending into said reflector tubes, and tubular holder members slidably telescoping said reflector tubes and having openings therein in registration with the openings in said reflector tubes.

5. In a jewelry display device comprising 80 a base, spaced tubes fixedly mounted upon said base, and having openings therein, illuminating means within said tube, tubular holder members slidably telescoping said tubes, and having openings therein in register 85 with the openings in said tube, and over which the jewels to be displayed are positioned, and a lining of heat insulating material on the inner side of said tubular holder member.

In testimony whereof I affix my signature. 90
CLARENCE H. SCRUGGS.
